(57) CLAIM

The ornamental design for a protective crib liner as shown and described.

DESCRIPTION

FIG. 1 is a perspective view of the protective crib liner; FIG. 2 is a front elevational view thereof; the rear elevational view is a mirror image of the front elevational view thereof;

FIG. 3 is a bottom plan view thereof; the top plan view is a plain and unornamented bottom, which is not shown; and, FIG. 4 is a right elevational view thereof showing my design; the left side view is a mirror image of the right elevational view thereof.
